PISTON FOR INTERNAL COMBUSTION MOTORS

Elmer C. Long, Grosse Pointe Park, Mich.

Application July 30, 1932, Serial No. 626,364
Renewed July 6, 1937

11 Claims. (Cl. 309—13)

This invention relates to certain improvements in a piston for an internal combustion motor and particularly that class of pistons made from an aluminum alloy and is a furthering of the invention disclosed in my U. S. Letters Patent 2,068,341, for Piston, dated January 19, 1937, the invention of this application having for its primary object to provide the piston with a flexible part in its skirt and with means extending from the opposite side of the piston to the flexible part for tending to hold the flexible part from moving too far outwardly as the piston expands under heat.

Another object of the invention is to provide the piston with a flexible skirt portion and with transversely disposed portions below the head which cooperate with the flexible portion of the skirt.

A further object of the invention is to provide the piston with a flexible skirt portion and with transversely disposed portions of material different from the piston which extend from one side of the piston skirt beneath the head to the flexible portion of the skirt.

A still further object of the invention is to provide the piston with a flexible portion on one side which is provided by slotting the piston and with transversely disposed metallic strips of material different from that of the piston which are molded with the piston and which are disposed above the pin bosses and in cooperable engagement with the flexible portion of the skirt and the opposite side of the skirt.

Other and further objects will appear in the specification and be specifically pointed out in the appended claims, reference being had to the accompanying drawing, exemplifying the invention, and in which:—

Figure 1 is an elevation of this improved piston on the flexible side thereof.

Figure 2 is a transverse vertical section taken approximately on the line II—II of Fig. 1.

Figure 3 is a transverse vertical section taken approximately on the line III—III of Fig. 2.

Figure 4 is an inverted horizontal section taken approximately on the line IV—IV of Fig. 3.

Referring by numerals to the accompanying drawing, 1 designates the head of the piston which is cup shaped and having the side wall 2 and formed in said side wall are the packing ring grooves 3 and extending from the side wall is a skirt 4.

The pin boss sides 5 of the piston skirt 4 beneath the wall 2 is relieved or cut in as designated at 6 around the pin bosses 7, each of which

is inwardly extended from respective pin boss sides 5 and formed in each pin boss side above each pin boss is a cored opening 8.

The skirt 4 on one side between the pin boss sides 5 is provided with a tongue shaped portion 9 which is formed by a pair of longitudinal slots 10 which are joined at one end by a transverse slot 11, the transverse slot 11 being formed adjacent the lowermost packing ring recesses 3 and whereas the longitudinal slots 10 extend to a point approximately below the pin bosses 7.

Extending from the open end of the piston and to a distance in the tongue shaped portion 9 is a longitudinally formed slot 12, said slot at its inner extending end terminating at a distance from the transverse slot 11. The forming of the tongue 9 in one side of the piston and the longitudinal slot 12 therein provides a flexible side 13 in the piston skirt 4.

The side of the skirt opposite from the flexible side 13 is the thrust side 14 and embedded in the thrust side 14 of the piston are the angular formed ends 15 of a pair of transversely disposed members 16, said members having their opposite angular ends 17 embedded in the tongue portion 9 of the flexible side 13 of the skirt. The pair of members 16 are of a material such as steel, having a much less co-efficient of expansion than aluminum alloy of which the piston, with the exception of the members 16, is made, and are disposed above the pin bosses and beneath the wall 2 of the head 1.

The members 16 are each beveled on their lower edges as designated at 18, said beveled edges being in engagement with respective projections 19, one of which is formed on the top side of each pin boss 7 and in abutment with the top edge of each member 16 is a respective web 20, said webs depending from the head 1 and extending thereacross. Depending from the head 1 and disposed between the webs 20 and formed integral therewith is a pair of webs 21 and in sidewise connection with each of the webs 20 and depending from the head 1 is a pair of legs 22, each pair of legs at their lower ends being 45 formed integral with respective pin bosses 7.

In the manufacture of a piston of this improved character which is preferably die cast, a pair of oppositely sidewise disposed metallic cores are inserted in the mold, said cores engaging at their ends in the aperture 23 of respective members 16 for holding the members in place. Another core or cores is then inserted longitudinally through the lower end of the mold and the mold is then ready for the pouring operation.

After the piston has been cast, the transverse slot 11 is formed by saw cutting and the cut in addition to passing through the wall of the piston skirt will also cut through the lower portions 5 of the webs 20 at one end as shown in Fig. 2, and longitudinal saw cuts provide the slots 10. Before cutting the slot 12, an aperture 24 is drilled in the side 13 of the piston and the slot 12 is then formed so as to terminate in the aperture 24. 10 This aperture is for the purpose of forming a terminus for the slot 12, so that the slot will not tend to extend further by splitting which might be brought on in the operation of the piston by flexing of the side 13 of the skirt. 15 In the operation of a piston of this improved character in a cylinder of an internal combustion motor, the head 1 obviously will receive more heat than the remaining part of the piston, and as the head expands diametrically across the pin 20 boss axis, the pin bosses will tend to be carried outward by the pairs of legs 22 depending from the head and the central portion of each of the members 16 will tend to be moved outwardly from one another thereby tending to shorten the 25 length of said members and as the members 16 are connected at 17 to the tongue portion 9 on the flexible side 13 of the piston, said members will tend to draw or hold the tongue portion 9 inward. As the piston head 1 is smaller in diameter than the skirt 4 and the pin boss sides 5 are relieved as designated at 6, the longitudinal slot 12 will provide means for relieving excess 30 expansion of the lower part of the skirt 4 across the pin boss sides and the pulling in tendency of 35 the members 16 on the tongue portion 9 will tend to constrain the thrust sides of the piston and particularly the flexible side 13 from excess expansion.

The engagement of the webs 20 with the upper 40 edges of the members 16, and the engagement of the lower edges of the webs with the top sides of the pin bosses 1 will prevent distortion of the members 16, and the projections 19 will tend to pull the intermediate portions of the members 45 outwardly from each other as the pin bosses are moved outward by expansion of the head.

On account of the manner in which the members 16 engage the webs 20 and 21 and the pin bosses 1, said members 16 are free to slide with 50 respect to said webs and the pin bosses. This 55 slideable relation of the members 16 will permit them to exert a pulling tendency on the tongue shaped portion 9 as said members are pulled by the action of the normal expansion of the thrust side 14 of the piston. As the tongue shaped portion 9 is flexibly connected to the skirt 4, the tongue shaped portion 9 will therefore always follow the bearing side 14 and consequently the 60 diameter of the skirt will remain approximately the same during thermal conditions of the piston.

While but one illustrative embodiment of the invention has been described in detail, it is not my intention to limit its scope to that particular embodiment or otherwise than by the terms of 65 the appended claims.

What I claim is:—

1. A piston comprising a head and a skirt having opposing thrust sides, said skirt being slotted on one of its thrust sides for providing a flexible 70 portion therein, a pair of transverse members of a material having a low coefficient of expansion connecting said flexible portion to the opposite side of the skirt, and a pair of webs depending from the head and having their lower ends in 75 abutment with the top of respective members.

2. A piston comprising a head having a side wall and a skirt having opposing thrust sides, one of the thrust sides being flexibly formed and separated from the side wall of the head and the other thrust side being continuous with the side 5 wall of the head, a pair of transverse members of a material having a low coefficient of expansion connecting said flexible thrust side to the opposite thrust side of the skirt, and a pair of webs depending from the head having their lower 10 ends in abutment with the top of respective members.

3. A piston comprising a head having a side wall and a skirt having opposing thrust sides, opposing pin boss sides in the skirt and a pin boss 15 extending from each pin boss side, one of the thrust sides being flexibly formed and separated from the side wall of the head and the other thrust side being continuous with the side wall of the head, a pair of transverse members of a 20 material having a low coefficient of expansion connecting said flexible thrust side to the opposite thrust side of the skirt, each member having bearing association with a respective pin boss, and a pair of webs depending from the head having 25 their lower ends in abutment with the top of respective members.

4. A piston comprising a head and a skirt having opposing thrust sides, said skirt being slotted on one of its thrust sides for providing a flexible 30 portion therein, a transverse member of a material having a low co-efficient of expansion connecting said flexible portion to the opposite side of the skirt, and a web depending from and extending across the head and having its lower 35 end in abutment with the top of said member.

5. A piston comprising a head having a side wall and a skirt having opposing thrust sides, one of the thrust sides being flexibly formed and separated from the side wall of the head and the other thrust side being continuous with the side 40 wall of the head, a transverse member of a material having a low coefficient of expansion connecting said flexible thrust side to the opposite thrust side of the skirt, and a web depending from the head and having its lower end in 45 abutment with the top of said member.

6. A piston comprising a head, a skirt having opposing thrust sides, and strut means of material different from the skirt connected to said 50 thrust sides and substantially abutting a part extending across the piston head and being capable of independent longitudinal movement relative to said part.

7. A piston comprising a head, a skirt having opposing thrust sides, web means depending from the head, and strut means having a low coefficient of expansion joining said thrust sides and disposed in substantial paralleling abutment with said web means and being free of interlocking engagement with said web means. 55

8. A piston comprising a head having a ringland, a skirt having opposing thrust sides, web means depending from and extending across the head and joining the ringland, and strut means having a low co-efficient of expansion joining said thrust sides and disposed in substantial paralleling abutment with said web means and said strut means being free to slide relative to said 60 web means.

9. A piston comprising a head, a skirt having opposing thrust sides, and strut means connected to said thrust sides and extending across the head and substantially abutting a part of said 70 head. 75

head, said strut means being free of interlocking engagement with said head.

10. A piston comprising a head, a skirt having opposing thrust sides, and strut means of material different from the skirt connected to said thrust sides and substantially abutting a part across the piston head, said strut means and said part with which it substantially abuts, being capable of free movement relative to one another.

11. A piston comprising a head having a side wall, a web integral with said head and its side wall, a skirt having a pair of thrust sides, one of said thrust sides depending from the side wall

of the head and the other thrust side having a tongue portion with its free end disposed adjacent the bottom of the head side wall, and a transverse member of a material having a low coefficient of expansion fixed to the free end of the tongue portion and extending to the opposite thrust side and fixed thereto in a plane beneath the head side wall, said member abutting said web and providing means for maintaining an approximately constant diameter across the thrust sides when the piston contracts or expands. 5
